UNITED STATES PATENT OFFICE.

ULRICH EBERHARDT, OF NEWARK, NEW JERSEY.

DESIGN FOR A FRAME FOR SPRUE-CUTTING MACHINES.

SPECIFICATION forming part of Design No. 24,371, dated June 4, 1895.

Application filed April 15, 1895. Serial No. 545,820. Term of patent 14 years.

To all whom it may concern:

Be it known that I, ULRICH EBERHARDT, a citizen of the United States, residing at Newark, Essex county, New Jersey, have invented 5 a certain new and useful Design for Frames for Sprue or Gate Cutting Machines, fully described and represented in the following specification and the accompanying drawing, forming a part of the same.

10 This design consists in a novel shape and configuration for the frame of a sprue or gate cutting machine.

The annexed drawing exhibits a perspective view of such sprue or gate cutter frame.

15 The frame is formed with legs A at the right and left sides leaving interspace B, with goose neck C extended upward from the tops of the legs, and pans D at opposite sides of the base of goose neck. The goose neck is shaped in

front at the bottom with an upwardly projecting cutter support E, and at the top with a downwardly projecting guide F having vertical channel in its outer side. 20

The essential features of the design are, the form of the legs, the pan, and the goose neck 25 with its upwardly projecting support E and its downwardly projecting guide F.

What is claimed herein is—

The design for the frame of a sprue cutting machine, as herein shown and described. 30

In testimony whereof I have hereunto set my hand in the presence of two subscribing witnesses.

ULRICH EBERHARDT.

Witnesses:

E. N. EBERHARDT,
THOMAS S. CRANE.
